UNITED STATES PATENT OFFICE

144,459

DESIGN FOR A COMBINED PENCIL AND ERASER

Stanley Iwanowicz, Detroit, Mich.

Application September 15, 1945, Serial No. 122,114

Term of patent 7 years

(Cl. D74—24)

To all whom it may concern:

Be it known that I, Stanley Iwanowicz, a citizen of the United States, residing at Detroit, in the county of Wayne and State of Michigan, have invented a new, original, and ornamental Design for a Combined Pencil and Eraser, of which the following is a specification, reference being had to the accompanying drawing, forming a part thereof, in which,

I claim:

The ornamental design for a combined pencil and eraser, as shown.

STANLEY IWANOWICZ.
